TIMER-ACTUATOR

William H. Kuntz, Dayton, Ohio

Application December 20, 1948, Serial No. 66,309

16 Claims. (Cl. 161—1)

1

This invention relates to a timer-actuator or such device that performs an act of power actuation after a designated interval of time.

One object of the invention is to provide a simple compact and powerful device, which in its simplicity provides a single power device that both drives the timing mechanism and then performs the actuating function selected.

Another object of the invention is to provide a timer-actuator mechanism that can have its action member connected to the load only after the power assembly has been conditioned for performing the selected act.

Another object of the invention is to provide a mechanism of the class described in which the power means for performing the action must be fully charged before the load actuating member can be coupled with the device to be actuated.

Another object of the invention is to provide a timer-actuator embodying the maximum of safety, in that it can be coupled to a device to be actuated only by a definite and single sequence of acts, whereby the tripping of the device is certain to perform the intended operation.

Another object of the invention is to provide a unit with a quickly separable mounting plate whereby the actuator may be quickly transferred from one installation to another.

The foregoing objects and advantages are accomplished by providing a rugged structure of simplicity demountable with respect to a mounting plate securely affixed to the article, or parcel, with which it is to be coupled. The mounting plate may be fixed to any type of load such as that designed to be lowered to the ground by means of a parachute or rotary wing device, or it may be fixed in relation to some mechanism that is to be operated in accordance with some time interval after an initiating impulse, such as operating a camera shutter, or setting off a charge of explosive, after a predetermined time interval. By such a means for coupling the timer-actuator with the mounting plate, it is feasible to have a less number of the actuator mechanisms, and shift them to the particular installation where they are needed at the time.

The timer-actuator unit itself, which is so readily movable from one mounting plate to another, is mounted within a rigid housing that also forms the framework of bearings and journals for the moving parts, thereby eliminating a number of small parts of structure. A hollow casing with one side open and fitted with a platform at the open side encloses the power developing means and the time interval means in such

manner the spring device furnishing the power and the gearing that it drives is rigidly supported to withstand shock of hitting the ground without displacing or misaligning the bearings. The cover being assembled and sealed prevents the entry of moisture and protects the working parts against corrosion and entry of dust or other particles that might interfere with the working parts. Disposed between the cover and the mounting plate are the safety levers and locks that insure that the actuator cable cannot be attached to the device to be actuated in its set condition until the power device is fully wound up. That also includes a device that requires the spring to be wound up before the selector for the time interval can be set. Thus, if the actuator cable is attached to the device to be actuated, and if the time is selected, then the unit must be in condition to operate as soon as the trip pin is released.

20 Further objects and advantages of the present invention will be apparent from the following description, reference being had to the accompanying drawings wherein a preferred embodiment of the present invention is clearly shown.

25 In the drawings:

Fig. 1 is a perspective view of a timer-actuator with the component parts arranged as if attached and set for tripping prior to its operation.

Fig. 2 is a top plan view of a timer-actuator shown in Fig. 1, but having the cap protecting the time selector and winding stem removed.

Fig. 3 is a vertical sectional view of the timer-actuator, substantially as indicated by the irregular line with arrows 3—3 of Fig. 2, the relation of parts being shown in power available condition.

Fig. 4 is a plan view of the mechanism as seen along the line and arrows 4—4 of Fig. 3 after the cover to the power mechanism has been removed, the parts being in the power expended relation ready to be wound up and set for a specific time interval.

Fig. 5 is a sectional view with parts broken away, somewhat as seen along the section line and in the direction of the arrows 5—5 of Fig. 3, the parts being in the power available condition.

Fig. 6 is an exploded view of the shaft assembly and selector assembly to aid in illustrating the operating mechanism.

Fig. 7 is a fragmentary view on an enlarged scale of the safety provisions by which the time selector cannot be set before the device is wound up for operation.

Fig. 8 is a similar view showing certain parts in a different position.

Fig. 9 is a fragmentary view in section through

the winding and selecting assembly showing the provisions for selecting the time interval and for withdrawing the actuator cable.

Fig. 10 is a fragmentary sectional view showing the relation of the protective cap when in place.

With particular reference to the drawings, 10 refers to a mounting plate designed to be attached to a parcel or structure from which, or in relation to which, some delayed action is to be performed. In order to best serve the purpose, the mounting plate 10 is provided with closely spaced holes 12 along its periphery and lending to securement to the parcel or structure by lacings or stitches such as in sewing with cords or strands. The mounting plate also provides larger holes 14 at the corners or other selected points receivable of a number of lacings, or even rivets, screws and the like by which the plate is adapted for other and rigid mounting. At each end of the mounting plate there is a strap or loop 16 and 17 of rigid material fixed at opposite ends by rivets or the like 18 and having the intermediate portion bowed away from the mounting plate 10 to provide a socket element receptive of a tongue or lug 20, 22 located on the opposite ends of a housing member 24.

The housing member 24 is of less overall length than is the distance between the straps, and the tongues 20, 22 are of unequal length, such that due to the flexibility of the mounting plate 10, the long tongue 22 may be inserted under its corresponding strap 17 far enough to permit the end of the short tongue 20 clearing the near edge of its corresponding strap 16, and permitting the housing member 24 then to be shifted endwise along the mounting plate to insert the short tongue 20 under its corresponding strap 16 to the position somewhat as shown in Figs. 2 and 3. A single screw 26 is then threaded through the strap 17 and the tongue 22 which definitely locates the housing member 24 with respect to the mounting plate 10, for a purpose presently to be explained.

The housing member 24 supports and encloses substantially all of the working parts of the timer-actuator as will presently appear. Seals are provided at all junctures so that the mechanism inside is protected against moisture, dust and gasses that might interfere with the fidelity of its operation. The housing member is of integral cast metal forming a rectangular box open on one side and there terminating in a rabbeted edge 28 that cooperates with the flange 30 of a cover 32, that joint, when finally assembled, being sealed with pitch or the like. The cover 32 is held in assembled relation with the housing member 24 by means of hold down screws 34 threading through corner apertures of the cover 32, thence through spacers 36 disposed between the cover and the corners of a platform 38 and into bosses 40 at the inside of the corners of the housing member 24. The hold down screws 34 also operate to secure anchoring clips firmly associated with respect to the unit as will presently appear in subsequent description, where further details of the housing and cover will be set out with respect to their associated features.

The platform 38 forms a supporting plate, and with the bottom 42 of the housing member 24 when secured together form the frame members for the power device and the timing mechanism enclosed within. Journals are provided in the platform 38 by through holes that align with pockets or cylindrical recesses drilled almost through the bottom wall 42, as shown in Fig. 3.

Thus, the power device consists of a winding shaft 44 and a relatively rotatable sleeve 46 concentrically associated and journaled at 48 and 50 in the platform 38 and bottom wall 42. The lower end of the winding shaft 44 provides a flange 52 between the bottom wall 42 and a non-rounded portion 54 received in a driving plate 56, the flange 52 spacing the driving plate 56 from the bottom wall 42. The driving plate 56 is circular in contour about the winding shaft 44 and has peripheral notches matching and cooperating with tongues and notches on the rim of a cup-like spring housing 58 whose end wall 59 is journaled about the sleeve 46, and the relation of parts is such that any torque applied to the shaft 44 is transmitted through 54 and 56 to the spring housing 58 and vice versa.

Completely enclosed within the spring housing 58 there is a spiral spring 60 whose outer end is anchored at 62 to the cylindrical wall of the spring housing, and whose inner end is anchored at 64 to the sleeve 46. The shaft assembly consisting of the winding shaft 44 and the sleeve 46 extend upwardly through the bearing 48 to cooperate with other parts not enclosed within the housing formed by the members 24 and 38. The sleeve 46 extends far enough above the platform 38 to provide a pair of driving tongues 66 engaging notches or recesses 67 at the center of a stop plate 68, the tongues 66 providing ratchet faces 70 cooperating with recesses in the end face of a cable spool 72 slidable and rotatable upon the winding shaft 44. That construction provides a rigid driving relation between the sleeve 46 and the stop plate 68, while the cable spool 72 has a one way drive connection with the end of the sleeve 46, but is rotatable in either direction relative to the winding shaft 44. The winding shaft 44 extends through the stop plate 68, the cable spool 72, and a selector knob 74 to end in a squared or other key receiving portion 76 accessible from outside of a turret portion 78 of the cover 32. Both the spool 72 and the selector knob 74 are slidable axially of and are reversely rotatable with respect to the winding shaft 44, but are urged in one direction along the winding shaft 44 by means of a spring 80 engaging the inside of the top 82 of the turret and a flange 84 of the selector knob. The spring 80 pushes the knob 74 downward against the spool 72 and the latter downward against the driving tongues 66.

Attached to the selector knob 74, such as by the flange 84, there is a depending web 86 having a pin-like end 88 extending through an arcuate slot 90 in the platform 38 to engage in any one of a plurality of holes 92 in a gear 94. The gear 94 is journaled to rotate on the sleeve shaft 46 between the platform 38 and the end wall 59 of the spring housing 58, with which the gear 94 has a one way driving relation through leaf springs 96 secured to the gear 94 and ratcheting into notches 95 on the end wall of the spring housing 58. The gear 94 meshes in driving relation with a pinion 98 on a shaft 100 journaled at 102 and 104 in the platform 38 and bottom wall 42, and driving a gear 106 which in turn drives a second pinion 108 on a shaft 110 journaled at 112 and 114 to rotate an escapement wheel 116 cooperable with the pallets 118 and 120 on an arm 122 secured to a shaft 124 journaled at 126 and 128. By that arrangement, the gear 106 is disposed in the space provided by the spacing flange 52, and the remaining of the gear train for the timing mechanism is compactly arranged. To provide for adjustment of the escapement device, the

journal 126 for the shaft 124 is provided at a point eccentric of the center of a disc 130 rotatably secured in the platform 38, so that rotation of the disc 130 will move the pallets 118 and 120 inward or outward with respect to the teeth of the escapement wheel 116. When adjustment is satisfactory, staking of the surrounding metal of the platform 38 into the screwdriver slot of the disc 130 will secure it against movement. The arm 122 terminates in weight member 132 of sufficient mass to retard the ratcheting of the pallets 118 and 120 over the teeth of the escapement wheel. The arm 122 also provides a crotch or receptacle 134 for engagement with a pin, rod or like device 136 for restraining operation of the escapement, such as before tripping.

The device 136 may be a rigid member attached to the end of a cable 138 or the like, but in all events is guided in a hollow boss 140 extending from the end of the housing member 24, such that when in place the member 136 interrupts the oscillation of the arm 122 and movement of the escapement wheel 116. If operation of the escapement is prevented, then the gear 94 can not be driven by the spring 60, wherefore the operation of the timer-actuator is wholly controlled by the member 136. The power device can be energized, that is, the spring 60 can be wound up by means of the appropriate key 142 inserted within the countersink 144 of the knob 74 and fitted over the squared portion 76 of the winding shaft 44. Looking down on the top of the timer-actuator unit, winding is accomplished by turning the shaft 44 in a clockwise direction, and that drives the spring housing 58 in a clockwise direction to ratchet beneath the gear 94 which is held against turning by the pin 136 engaging the crotch 134. During this winding the inner end of the spring 60 is held fast by the sleeve 46 which is prevented from turning by reason of the lock plate 68 whose notches 67 receive the driving tongues 66 of the sleeve 46. The lock plate is so called because of the peripheral notch 146 that is engaged by the lock arm 148 carried by a shaft 150 and pivoted in the housing and its platform. A spring 152 wound about the shaft 150 bears against the sidewall of the housing 24 and urges the arm 148 against the edge of the lock plate 68 and into the notch 146 when they are in radial alignment.

When the power spring 60 is about fully wound up, the outermost turn of the spring 60 withdraws from engagement with the inside of the spring housing 58 to uncover a slot 154 in the spring housing through which an arm 156 projects. The arm 156 is carried by a shaft 158 journaled in the housing members and projects upward through the mounting plate 38 to carry a cam lever 160. As the cam lever 160 oscillates in response to the lever 156 falling into the slot 154, it swings the tail end 162 of a safety latch 164 in a clockwise direction to withdraw the hook 166 from a notch 168 in the edge of lower flange 170 of the spool 72. The flange has three such notches into any one of which the hook 166 may fall when the lever 156 is riding on the periphery of the spring housing 58. Since the lever 156 can enter the notch 154 only when the spring has been tightly wound up so that the outside turn of the spring is withdrawn from the aperture, then it is obvious that the hook 166 can be removed from one of the notches 168 only when the spring is fully wound up. The relation of the parts for that safety feature is shown in Figs. 5 and 8, where the latch lever 164 is pivoted at

172 to the mounting plate 38 and has a leaf spring 174 anchored to it and bowed to have one lap or free end pressing against the end of the cam lever 160 such as at 176. While the hook 166 is seated in one of the notches 168 the spool 72 cannot be rotated in a counterclockwise direction which must be done in order to unwind an actuator cable 178. As shown in Fig. 5 the cable 178 comes in from the left and is secured at its end to the flange 170 at 180, so that it may be wound around the spool when the spring 60 is finally released.

To determine the period of time after the initial tripping by withdrawal of the pin 136 at 15 which the cable 178 will be actuated, the knob 74, Fig. 3 and Fig. 9, is pulled outwardly and rotated to the indicated number on the scale marked on the upper face of the turret 78 of the cover 32 as shown in Fig. 2. To facilitate that selection the knob 74 has a pointer 182 which is disposed over the point 88 on the lower end of the web 86. To start with when the time selection is made, the point 88 occupies the end hole 92a, that is at the zero position of the scale, or against the right hand end of the arcuate slot 90, as indicated in Fig. 7 in dotted line section. While in that position, the lever 148 is held outward free of the notch 146 of the lock plate 68, which is the stop position of the power device after it has actuated the cable. Pulling outward of the knob 74 withdraws the point 88 from that hole 92a in the gear 94 sufficient to permit turning the knob to any other hole of the series that are exposed through the arcuate slot 90, providing the safety lever hook 166 is withdrawn from the notches 168 of the flange 170. But since the hook is withdrawn only when the spring is fully wound up, the selection for time can be made only when the spring is wound up. These features are shown in the fragmentary showing of Fig. 7, where the web 86 is shown in the angular space between the end of the slot 90 and the end of the lever hook 166.

Thus, when the power spring 60 is unwound, no appreciable amount of time for operation can be selected, but the pin 88 can be removed from a position holding the lock lever 148 released, sufficient to permit engagement of the lock and wind of the power device as will presently appear.

When the knob 74 is raised or pulled outwardly it slides on the winding shaft 44 to compress the spring 60 and also raises the spool 72 to disengage the driving tongues 66. If the safety hook 166 is disengaged from the notch 168 when the spool is raised, then the cable 178 may be pulled out. Extending radially inward from the web 86 there is a tongue or lug 184 that is disposed beneath the upper flange 186 of the spool 72, and which acts to pull the spool 72 away from the lock plate 68 somewhat as shown in Fig. 9. The pin 88 is now withdrawn from one of the holes 92 in the gear 94 sufficient that the knob may be turned to another hole. The camming portion 60 of the web is still wide enough and low enough that release of the knob will not permit the web to hang up on the top of the lever 164. The web 86 is reduced at shoulder 188 to join the pin 88. The lever 164 is also thick enough at the hook end 166 that the flange 170 will not be disengaged at the notch 168 in case the knob and spool are raised while the power spring 60 is unwound.

To protect the selector knob and the winding shaft, to guard against any accidental derangement of the device when wound and set for op-

eration, and to complete the hermetical seal of the timer-actuator, a cap 190 fits over the knob 74 where it is retained by headed pins 192 secured to the top 82 of the turret 78. As shown in Fig. 10, the inside of the cap 190 carries a compressible seal ring 194 such as resilient rubber or rubber-like material, that engages the face of the turret top 82 and is somewhat compressed as the cap is depressed to enter the heads of the pins 192 in the round part of key-hole shaped slots 196 in the face of the cap 190. That depression of the cap not only compresses the ring 194 but also approaches the face of the knob 74 so closely that the knob cannot be displaced enough to permit withdrawal of the pin 88 from the holes 92 clockwise rotation of the cap holds the parts in that relation. Thus, no change in the setting or winding of the timer-actuator can be made until the cap 190 is removed. Neither can any foreign matter like dust and moisture enter the unit to interfere with its working properly.

When the timer-actuator is completely assembled, particularly as shown in Fig. 1, clamp brackets 198 and 200 are attached at each end of the housing assembly by means of the hold-down screws 34. The bracket 198 provides a half cylindrical loop 202 mating with a similar reversed loop on a clip 206 beneath it, that secures one end of a flexible armor 208 when clamped to the bracket 198 by screw devices 210. A rubber-like grommet 212 carried by the circular wall of the turret is disposed about the actuator cable 178 which also passes through the armor 208 to end with a fitting 214. The free end of the armor 208 is fitted with a ferrule 216 to protect the sharp edges and make for smooth entry of the fitting 214 when the cable 178 is being assembled. The bracket 200 is secured to the opposite end of the unit by the screws 34 and cooperate with a similar clip 218 held together by screw devices 220 to clamp the end of an armor 222 that encloses the trip element 136. A resilient rubber sleeve 224 frictionally engaging over the guide boss 140 also fits sufficiently tight over the trip element 136 when it is in place that the seal of the housing for the unit is complete.

The timer-actuator unit, wound, set, and properly conditioned for performing a selected operation is illustrated in Fig. 1. When the timer-actuator unit is completely assembled it is characterized by having a standard length or dimension between a pair of reference points, such as from the center of screw 26 to the socket 226 of the fitting 214, when the cable 178 is fully withdrawn from the spool. A connecting member 230 with its terminal member 228 is coupled to the fitting 214 to provide the additional length necessary to hook onto the device to be actuated. Thereby, the necessary length or distance between the reference point 25 and the point of connection to a device to be operated is made up by the standard length of the timer actuator unit plus a certain length of the member 230, whose free end is usually fitted with a quick disconnect element cooperating with a suitable part on the device to be operated, such as the pin lock for a parachute release. Adaptation of the timer-actuator unit to a different type of installation only involves pulling the terminal connection 214, 228 from the armor 208, disconnecting the member 230 and replacing it with one of the proper dimension.

8 Operation

Assuming that the timer-actuator unit is properly secured to the mounting plate 10 and in the power expended condition, the spring 60 will be completely unwound and the actuator cable 178 will be wound about the spool 72 between the flanges 170 and 186. The lever 156 will be riding somewhere along the outer periphery of the spring housing 58 which biases the safety latch 164 into engagement with the notch 168 of the spool flange 170. The selecting pin 88 will be disposed in the end or zero hole 92, as indicated by dotted lines at 92a in Fig. 7. The lever 148 will be held disengaged from the notch 146 as shown in Fig. 7, by the web 86 of the selector knob when the pin 88 is in hole 92a, though the web is shown in the hole 92c for other reasons. The lock lever 148 therefore will not engage the edge of the lock plate 68. The cable 178 will be wound about the spool 72, and the cap 190 will be in place as shown in Figs. 1 and 10. The trip pin 136 will be withdrawn from the crotch 134. These are the conditions of the unit just after the power device has expended itself.

To condition the unit for a subsequent operation a definite sequence of actions should be made and some actions must be made in a definite sequence. It is desirable that the trip pin 136 be first inserted in the boss 140 to engage the crotch 134 which prevents movement of the timing gear train. That prevents the gear 94 moving. The cap 190 is rotated counter-clockwise to disengage the pins 192 from the narrow part of the slots 196, so that the cap may be withdrawn from over the knob 74 to expose the knob and the winding stem 44. The cap 190 must be removed before either the power device can be wound up or the time of delay can be selected. Before the spring 60 is wound up the knob is pulled outward and turned clockwise far enough to disengage the web 86 from the lever 148 and let it engage the edge of plate 68. That will locate the pin 88 in one of the holes 92b or 92c as shown in Fig. 7. It cannot be moved further because of engagement with the end of the lever 164 whose hook 166 now engages in the notch 168 of the spool. The slight movement of the selector pin from the hole 92a permits the end of lock lever 148 to ride on the periphery of the lock plate 68. Applying the winding key 142 to the squared portion 76 of the winding shaft 44 permits rewinding of the spring 60.

Winding is accomplished by turning the shaft 44 in a clockwise direction. The shaft assembly will rotate clockwise with the spring housing ratcheting against the detent springs 96 carried beneath the gear 94. Soon the lock plate 68 will turn far enough that the end of the lever 148 engages the notch 146 and forms a positive stop for further rotation of the sleeve 46 and the inner end of the spring 60. Further rotation of the shaft 44 causes the spring to be rewound as shown in Fig. 3. It must be fully rewound so that the outermost turn withdraws from against the inside of the spring housing 58, such as shown in Fig. 5. That permits the end of lever 156 to enter the slot 154 of the spring housing 58 which permits rocking of the shaft 158 and rocking of the cam lever 160 in a counter-clockwise direction which rocks the safety lever 164 clockwise and withdraws the hook 166 from the notch 168, substantially as shown in Figs. 5 and 8. Only now, may the web 86 be moved past the hook 166 of the lever 164,

Selection of the interval for operation of the timing device is now made by pulling the knob 74 outward of the cover 32 and rotating to the hole 92 desired, and as indicated by the scale on the face of the turret 18 of Fig. 2. There the pointer 182 indicates a selection of 26 seconds that must elapse after removal of the trip element 136 before the lock lever 148 is lifted. In Fig. 7, the pin 88 is shown as disposed in hole 92c which by comparison with the scale shown in Fig. 2, indicates a selection for 3 seconds. Whatever the selection, the pin 88 which is directly beneath the pointer 182, is disposed in one of the holes 92 when the knob is released. At the time that the knob 74 is raised up for selection of the time interval, the spool 72 is also raised from the lock plate 68 as shown in Fig. 9. The safety hook 166 being withdrawn from the notch 168 as shown in Fig. 5, the actuator cable 178 may now be withdrawn or unwound from the spool 72 by pulling of the member 230. With the spring fully rewound, and the time selection having been made with the actuator cable pulled out as far as it will come, the actuator cable can be attached to a new device, or the device incorporating the element 230 can be reset for operation. The protective cap 190 is then replaced and secured by a slight turn. Nothing can then unintentionally disturb the unit. To set the actuator unit into operation, the trip pin 136 is removed from its holding position in the crotch of the arm 122. That releases the escape mechanism so that the gear 94 may now drive the time gear train. The gear 94 now rotates in a counter-clockwise direction as viewed in Fig. 5 and carries with it the selecting pin 88 and attached web 86 to something like the position shown in Fig. 8 where the web 86 by reason of its angular inclination cams past the hook of the safety lever 164 and finally engages the side of the lock lever 148. The lever 148 is cammed outwardly as the web moves on to the end of the slot 90, until the end of the lever is disengaged from the notch 146. That condition of the lever 148 is shown in Fig. 7. The remaining energy of the spring 60 now drives the spool 72 in a clockwise direction with such surge of power that a very forceful yank or tug is delivered to the actuator cable 178 which operates the device incorporated with the element 230.

While the embodiments of the present invention as herein disclosed, constitute preferred forms, it is to be understood that other forms might be adopted, all coming within the scope of the claims which follow.

What is claimed is as follows:

1. In a timer-actuator for effecting operation of a device at the end of a time interval after a predetermined initiation, the combination comprising, a mounting plate permanently fixed on and relative to the device to be operated, a power driven actuator assembly removably secured to the mounting plate and having an actuator cable adapted to be coupled with the device to be actuated, a spool driven by the power assembly for storing the actuator cable, means for activating the power driven assembly, and means preventing withdrawal of the stored cable and delaying the coupling of the actuator cable with the device to be actuated until the power driven assembly has been fully activated whereby the timer-actuator can be operatively connected with the device to be operated only if the power means is sufficiently reactivated with sufficient energy to effect the desired operation when initiated.

2. In a timer-actuator for effecting operation of a device at the end of a time interval after a predetermined initiation, the combination comprising, a mounting plate secured at a fixed distance relative to the device to be operated, an actuator assembly removably secured to the mounting plate and adapted to be quickly shifted from one plate mounting to another, said actuator assembly having a time consuming gear train, a spring power device for actuating the train, trip means for restraining the train against movement by the power device, a selector means for determining the extent of time the train will be driven after the trip is actuated, a spool and cable adapted to be driven by the same spring power device as soon as the selected time interval has elapsed, and safety means insuring that the spring power device is fully restored each time before that cable on the spool can be withdrawn to be coupled with the device to be actuated.

3. In a timer-actuator, a housing including a pair of spaced walls, a power device providing a concentric shaft and sleeve journaled in the said walls, a power spring yieldably coupling the shaft and sleeve for relative angular movement, a time gear train to be driven by said shaft, means for selecting the interval that the time gear train shall be driven, a cable spool to be driven by said sleeve, means for resisting drive of the cable spool until the selected interval of time gear train has elapsed, means for withholding the start of time gear train, and means including a part of said selecting means for overcoming the said resisting means to start the drive of said cable spool, and means responding to the spent condition of said power spring for preventing the selection of an interval of time for the time gear train until the power spring has been restored to its full efficiency.

4. In a timer actuator, a pair of spaced plates, a power device disposed between the plates and journaled therein, said power device including a winding stem, a concentric sleeve and a coiled spring connecting the stem and sleeve for relative rotation, a gear train disposed between the plates and having a driven gear journaled concentric of the sleeve, said sleeve and stem extending through one of the plates to receive a lock plate and spool respectively, driving means between the lock plate and the sleeve, said spool being journaled on the stem and having a one way drive connection with said sleeve extension, a lock lever on one of said plates operable to prevent rotation of said lock plate while said spring is being wound up, means operated by the said driven gear for displacing the lock lever after an interval of gear train operation, and means carried by the winding stem for selecting the time interval to elapse before the lock lever is displaced.

5. In a timer actuator, a pair of spaced plates, a power device disposed between the plates and journaled therein, said power device including a winding stem, a concentric sleeve and a coiled spring connecting the stem and sleeve for relative rotation, a time consuming gear train having a main gear with one way driving connections with said power device, lock means pivoted to one of said plates for releasably preventing rotation of the sleeve, a cable spool journaled on said stem and adapted for one way drive by said sleeve, selector means engageable with said main gear for determining the time of run for the time consuming gear train, and means in-

cluding a part of the selector means for displacing the lock means at the conclusion of said time of run.

6. In a timer-actuator, a pair of spaced plates, a sleeve shaft journaled for rotation in one of said plates, a winding shaft journaled for rotation in said sleeve and in the other of said plates, a power spring connecting the sleeve shaft and winding shaft for relative rotation, a time consuming gear train having a main gear driven by said winding shaft, a selector journaled on said winding shaft and engageable with holes in said main gear for determining the interval of run for the time consuming gear train, lock means preventing rotation of the sleeve shaft while the time consuming gear train is being driven, a cable spool rotatably mounted on the winding shaft and having a separable driven relation with said sleeve shaft, cam means incorporated in the lock means engageable by the selector means at the conclusion of run of the time consuming gear train for releasing the lock means whereby the remaining energy of the power spring will drive the cable spool to forcefully wind up the actuator cable.

7. In a timer-actuator, a pair of spaced plates, a sleeve shaft journaled for rotation in one of said plates, a winding shaft journaled for rotation in said sleeve and in the other of said plates, a power spring connecting the sleeve shaft and winding shaft for relative rotation, a time consuming gear train having a main gear journaled on the sleeve shaft and adapted to be driven by the winding shaft when the winding shaft rotates relative to the sleeve shaft, a cable carrying spool journaled on the winding shaft and adapted to be driven by the sleeve shaft when the sleeve shaft rotates relative to the winding shaft, releasable means preventing run of the time consuming gear train, releasable lock means preventing rotation of the sleeve shaft and cable spool while the time consuming gear train is in operation, selector means for determining the interval of operation of the time consuming gear train, means actuated by the selector means for releasing the lock means to then drive the cable spool, and means operated incident to an exhausted power spring preventing unwind of the cable and selection of a time interval of the run of the time consuming gear train until the power spring has been completely rewound.

8. In a timer-actuator for effecting operation of a member a selected time after an initial act is performed, a housing and platform rigidly secured together to provide a pair of parallel walls, a spring power device enclosed within the parallel walls and providing a pair of concentric shaft elements extending through the platform, a time consuming escapement located between the said walls and driven by the spring power device, means projecting into the housing for selectively arresting movement of the escapement means outside of the parallel walls for selecting the interval of time that the escapement will be driven, and means controlled by the status of the spring power device between the parallel walls that prevent the selecting of the time interval until the spring device has been restored to full available power.

9. In a timer-actuator for effecting operation of a member a selected time after an initial act is performed, a housing and platform rigidly secured together to provide a pair of parallel walls, a spring power device enclosed within the parallel walls and providing a pair of concentric

shaft elements extending through the platform, a time consuming escapement located between the said walls and driven by the spring power device, means projecting into the housing for selectively arresting movement of the escapement means outside of the parallel walls for selecting the interval of time that the escapement will be driven, a releasable lock device carried by the platform and engageable with one of said shaft elements, a cable spool to be driven upon release of said lock device, means including the other of said concentric shaft elements for winding the spring device, means restricting the selection of time interval until the spring device has been fully rewound, and means actuated at the concluding end of the selected time interval of escapement run for unlocking the releasable lock device.

10. In a timer-actuator for effecting operation of a member a selected time after an initial act is performed, a housing and platform rigidly secured together to provide a pair of parallel walls, said housing comprising an open sided box of integral construction and the platform closing the open side thereof, a spring driven escapement mechanism journaled in the housing and platform and disposed between the walls, there being a pair of shaft elements projecting through the platform, a notched plate driven by one of the shafts, a cable carrying spool rotatable on the other shaft but driven by the first identified shaft, means operable upon said other shaft for winding the spring driven escapement, a lever engageable with the notched plate for arresting its rotation, means for selecting the time that the escapement will run, and means for releasing the shaft lock at the conclusion of the escapement run.

11. In a timer actuator for effecting operation of a member a selected time after an initial act is performed, a housing and platform rigidly secured together to provide a pair of parallel walls, said housing comprising an open sided box of integral construction and the platform closing the open side thereof, a spring driven escapement mechanism disposed between and journaled in the housing and platform, there being a pair of shaft elements projecting through the platform, lock means engaging one of the shafts, a cable spool carried by the other shaft, and safety means engaging the cable spool to prevent unwind of cable until the spring driven escapement has been rewound, and cap and cover means cooperating with the said housing for enclosing the timer-actuator mechanism and isolating the working parts against the effects of foreign matter.

12. In a timer-actuator for performing an act of force a selected interval of time after a tripping member is actuated, a cable carrying spool, a spring powered device for driving the spool, having a winding shaft and a driving shaft, an escapement gearing driven by the spring powered device, and including a main gear journaled on the driving shaft, time selecting means journaled on the winding shaft and having a pin engageable with a selected one of holes in the main gear, lock means restraining rotation of the driving shaft when the winding shaft is being rotated to wind the spring powered device and when the spring powered device is driving the escapement gearing, means including a part of the time selecting means for releasing the lock means at the conclusion of the escapement run so that the remaining energy of the spring powered device will drive the cable carrying spool.

13. The combination set forth in claim 12 wherein case elements completely enclose the

mechanism, a tripping member extends through one of the case elements to engage the escapement gearing, a flexible cable extends through one of the case elements to connect with the cable carrying spool, and a knob extending through one of the case elements to actuate the time selecting means, sealing means at all junctures of the case members, and seal means embracing all extensions into the case elements to isolate the working mechanism against outside matter.

14. In a timer-actuator for performing an act of force a selected interval of time after a tripping member is actuated, a cable carrying spool, a spring powered device for driving the spool, having a winding shaft and a driving shaft, an escapement gearing driven by the spring powered device, and including a main gear journaled on the driving shaft, case members enclosing the spring powered device and the escapement gearing, said winding shaft and driving shaft being concentric and having a journal bearing in one of said case members, a notched plate driven by an extension of said driving shaft, a lock lever pivotally supported by said one case member and adapted to arrest movement of said notched plate, said cable carrying spool being rotatably supported by an extension of the winding shaft and adapted for one way drive by said driving shaft, a selector knob rotatable upon the extended winding shaft and having an arm spanning the cable carrying spool and the notched plate to engage within any one of a series of holes in the main gear of the escapement gearing, the said one case member having an arcuate slot concentric with the journal of said shafts, through which arcuate slot the selector arm may pass to enter the selected hole in the main gear, and along which arcuate slot the arm may travel while the spring powered device is driving the escapement gearing.

15. In a timer-actuator, a pair of concentric shafts, a spring housing drivingly connected with one of said shafts, a coil spring connected at its ends to the spring housing and to the other of the shafts whereby the concentric shafts are relatively rotatable within the limits of the connected spring, case members rotatably supporting the shafts, said shafts extending through one of the case members, a gear in clutching engagement with said spring housing and journaled about the extension of said shafts, escapement means driven by said gear, a cable carrying spool rotatable upon the extension of one of said shafts and having clutching engagement with the other of said shafts, a knob and pointer axially and rotatably movable on one of said shaft extensions and having means engageable with the

spool for disengaging the clutching engagement with said other shaft, means for winding the spring to drive the escapement means and to rotate the cable carrying spool at the conclusion of the escapement run, and means for selecting the time interval of escapement run only after the spring has been rewound, including a circular row of holes in said gear concentric with its journal on the shaft extensions, an arcuate slot in the case member concentric with the rotatable support for the shafts and disposed over the holes in said gear, an arm on said knob having a pin engageable in any of the holes of said gear, a lock lever pivoted to the said one case member and extending over one end of said arcuate slot to arrest rotation of said shaft adapted to drive the spool, a safety latch pivoted to said one case member and extending across the said arcuate slot to arrest rotation of said spool, and actuating means responsive to full rewind of the spring for withdrawing the safety latch from engagement with the cable carrying spool, said latch and lock lever being in the path of movement of said knob arm and adapted for camming movement by said arm while the escapement is being driven by the spring, said lock lever being released at the conclusion of the escapement run by the movement of said knob arm.

16. The combination set forth in claim 12 wherein case elements completely enclose the spring powered device and the escapement gearing and the time selecting means includes a knob journaled on the winding shaft and in one of the case members to be operated from without the case members, a protective cap secured to the said one case member to maintain the time selecting means in the selected position, to prevent disturbance of the selector knob, and to isolate the selector mechanism from any disturbing agencies so long as the cap is in place, seal means at all junctures of the case elements and a gasket compressed by the protective cap when in place to prevent the entrance of any foreign matter that might interfere with the proper working of the timer actuator when the unit is tripped for operation.
